UNITED STATES PATENT OFFICE.

ALFRED HILLYARD MITCHELL, DECEASED, LATE OF PLUMSTEAD, ENGLAND; BY HENRY ORMSBY BURGE, EXECUTOR, OF BRENTWOOD, ENGLAND, ASSIGNOR TO HENRY SIMON LIMITED, OF MANCHESTER, ENGLAND.

PNEUMATIC ELEVATOR.

Application filed September 2, 1921, Serial No. 498,071, and in Great Britain November 20, 1913.

(GRANTED UNDER THE PROVISIONS OF THE ACT OF MARCH 3, 1921, 41 STAT. L., 1313.)

This invention relates to pneumatic elevators operating on the suction or vacuum principle and particularly to devices for the extraction of grain or other material from the hopper of such elevators without the admission of free air thereto.

It has hitherto been usual to employ for this purpose either gravity tipping air-locks or rotary wheel valves. The former, that is to say, the tipping air-lock comprises a pivoted box or casing having two compartments with inlet openings at the top which work in conjunction with a discharge opening in the hopper and with outlet openings at their lower part. The grain is discharged from the hopper into the two compartments alternately and its weight causes the device to tilt or capsize. As such a tipper which is over-balanced by the weight of the grain is or the like being discharged, must be large enough to tip with the lightest class of grain, namely oats, it is obvious that when the same device is employed for discharging wheat, which is one and a half times heavier than oats, it will capsize when little more than half full, so that a considerable wastage of air is the result. A further disadvantage of this type of discharge device is that, as it must be sufficiently free to capsize by gravity, it is not possible to make a perfectly tight joint between it and the face of the hopper under which it works, so that there is always a certain amount of air leakage at this part. The tipper air-lock, however, possesses the advantage that as it has a deep receptacle of some size, large pieces of foreign matter, of which there is a considerable amount in grain, can pass into the same with only slight possibility of causing a stoppage.

In the case of the rotary wheel-valve, unless this is made abnormally large, the receiving pockets with which it is provided are comparatively small, so that any foreign substance of quite small dimensions, such as a nail or a piece of wood or sacking, which may fall on to the top of the grain or other material in the pocket when the latter is practically full, usually gets nipped between the knife edges formed by the divisions in the wheel-valve and the sliding faces in which it works, the result being that the ap-

paratus is put out of action. These wheel-valves, however, are always driven by power and the working faces, therefore, can be kept in contact sufficiently tight to make a good joint.

The present invention has for its object to provide a discharging or extracting device in which the advantages of both the above forms of apparatus are retained whilst their disadvantages are eliminated. To this end, according to the invention, use is made of a tipper divided into two compartments in the known manner, but which instead of capsizing under the action of gravity as has hitherto been the practice, is positively reciprocated by means of a crank and a connecting rod, by which means the rubbing faces of the tipper and hopper can make a sufficiently tight fit to prevent any wastage of air at that part.

In a suitable arrangement for carrying out the invention the tipper comprises a box having two compartments provided with a valve face at its upper part having inlets for the grain or other material and designed to move in contact with the valve face provided at the bottom of the hopper; the lower part of each compartment is provided with a valve or door, the face against which the said valve bears being so inclined that the valve or door of the up-coming compartment is always quite closed before that compartment is opened to the hopper, thus preventing any possible in-rush of free air into the vacuum chamber, a failing which is common to existing types of tipping devices. The tipper is designed to be positively reciprocated by means of a connecting rod actuated by a crank which is rotated at a suitable speed by any suitable gear.

In practice the connecting rod may be of an elastic nature so as to yield, should the apparatus become clogged, thereby preventing breakage.

To enable the invention to be fully understood, will be described by reference to the accompanying drawing, in which Figure 1 is a sectional side view of a tipping air-lock constructed according to the invention, Figure 2 is a sectional view at right angles to Figure 1, Figure 3 is a view of a detail hereinafter described, Figure 4 is a similar

view to Figure 1 of a modified construction, and Figure 5 is a plan of a detail thereof.

a represents the hopper of the grain or other pneumatic elevator and *b* is the tipping box which is pivoted at *c* and is divided into compartments *d* and *e* by means of the partition *f*. The upper part of the tipping box is provided with the valve face *g* having inlet openings *h* for the grain. This valve face *g* moves against the correspondingly shaped face *j* upon the bottom of the hopper *a*. Each of the compartments *d* and *e* is provided at its bottom with an outlet *k* for the grain or other material, having a face *l* against which bears the freely suspended valve or door *m*, the inclination of the face *l* being such that the door *m* of the compartment to which it is attached, completely closes against the said face *l* on the upward movement of that compartment before its inlet *h* passes beneath the usual air exhaust port or bypass *a*¹, thus preventing any possibility of free air passing into the vacuum chamber through the tipping box.

n is the connecting rod which is connected to the tipping-box *b* at the point *n*¹ below the pivot *c*, and *o* is the crank by means of which the said connecting rod is moved backwards and forwards so as to positively tilt the tipping box alternately in opposite directions. The crank *o* is continuously rotated by means of the worm gear *p* which is driven by the bevel gear *q* actuated in any suitable way.

The connecting rod *n* is preferably, as shown in section in Figure 3 made of an elastic nature for the purpose above described. For this purpose, it is divided into two parts one of which carries the sleeve *r* in which slides a piston *s* on the end of the other portion, springs *t* being fitted in the sleeve *r* upon either side of the piston *s*. These springs *t* are of sufficient strength to move the tipper over from one position to another without any appreciable compression or expansion taking place as long as the tipper can move under normal conditions. In the event of any foreign substance, however, becoming jammed in the apparatus, the springs are of sufficient length to be compressed or expanded as the case may be, to a sufficient extent to enable the crank to complete its revolution, thus obviating any injury to the apparatus, as the jammed material can fall clear into the upcoming tipper on the return stroke of the latter.

As will be obvious the crank and connecting rod gear used for reciprocating the tipping-box provides a motion in which there is a slight dwell or period of rest at the ends of the strokes or reciprocations, and this rest is what is in practice required. If, however, it is desired to lengthen this period the connecting rod *n* may be slotted as shown at *n*², thus providing for a certain amount

of lost motion and consequent increase of the terminal period or rest.

In the modified construction illustrated in Figs. 4 and 5 the connecting rod *n* is attached to a cross-head *u* wherefrom side rods *v* extend freely through sleeves *x* on a cross rod *y* which is pivotally mounted in lugs *z* on the tipping-box *b*. Springs *2* are mounted on the side rods *v* at either side of the cross rod *y* and bear against the sleeves *x* and stops *3* on the rods *v* to form a resilient connection between the side rods *v* and the cross rod *y* and allow of relative movement between the tipping box and the connecting rod *n* in case of the box jamming. The crank pin *o* which drives the connecting rod *n* is provided on a disc *4* which is rotated by appropriate gearing *5*.

In the gravitation type of tipper as hitherto used, strong buffers have to be made use of for absorbing shock on each drop of the tipping-box and the whole apparatus has to be made of considerable strength to withstand these shocks. The necessity of employing buffers is obviated by this invention since under the positive mechanical actuation of the tipper, the latter tilts without shock. Moreover, the reserve of space which is required in gravitation tippers as hitherto made for the reasons above specified is no longer necessary in the improved apparatus, which can, therefore, be made of less capacity than has hitherto been necessary, whereby unnecessary wastage of air is obviated.

What is claimed as the invention and desired to be secured by Letters Patent is:—

1. The combination with the mouth of a grain hopper, of an arcuate valve seat formed at said mouth and provided with an exhaust port, a tipper provided with an arcuate upper end fitting said seat and having spaced inlet ports, said tipper being divided into a pair of compartments into which said inlet ports respectively open, each of said compartments having a valve at its lower end, and mechanical means connected to the tipper for oscillating it at a definite rate regardless of the kind of grain being handled to bring each inlet port alternately into registration with the mouth and exhaust port and then out of such registration and permitting intervals of rest of said tipper between movements.

2. The combination with the mouth of a grain hopper, of an arcuate valve seat formed at said mouth and provided with an exhaust port, a tipper provided with an arcuate upper end fitting said seat and having spaced inlet ports, said tipper being divided into a pair of compartments into which said inlet ports respectively open, each of said compartments having a valve at its lower end, and mechanical means to effect oscillation of said tipper to bring each inlet port alternately into registration with the

mouth and exhaust port and then out of such registration, and including a rotating crank and a yieldable link connecting said crank and tipper.

- 5 3. The combination with the mouth of a grain hopper, of an arcuate valve seat formed at said mouth and provided with an exhaust port, a tipper provided with an arcuate upper end fitting said seat and having spaced inlet ports, said tipper being divided into a pair of compartments into which said inlet ports respectively open, each of said compartments having a valve at its lower end, and mechanical means to effect oscillation of said tipper to bring each inlet port alternately into registration with the mouth and exhaust port and then out of such registration, and including a crank and a link connecting the crank and tipper, the connection at one end of the link being a pin and slot connection whereby to permit rest of the tipper between successive movements.
- 10 4. The combination with the mouth of a grain hopper, of an arcuate valve seat formed at said mouth and provided with an exhaust port, a tipper provided with an arcuate upper end fitting said seat and having spaced inlet ports, said tipper being divided into a pair of compartments into which said inlet ports respectively open, each of said compartments having a valve at its lower end, and mechanical means to effect oscillation of said tipper to bring each inlet port alternately into registration with the mouth and exhaust port and then out of such registration, and including a crank and a link connecting the crank and tipper, the connection at one end of the link being a pin and slot connection whereby to permit rest of the tipper between successive movements.
- 15 5. The combination with the mouth of a grain hopper, of an arcuate valve seat formed at said mouth and provided with an exhaust port, a tipper provided with an arcuate upper end fitting said seat and having spaced inlet ports, said tipper being divided into a pair of compartments into which said inlet ports respectively open, each of said compartments having a valve at its lower end, and mechanical means to effect oscillation of said tipper to bring each inlet port alternately into registration with the mouth and exhaust port and then out of such registration, and including a crank and a link connecting the crank and tipper, the connection at one end of the link being a pin and slot connection whereby to permit rest of the tipper between successive movements.
- 20 6. The combination with the mouth of a grain hopper, of an arcuate valve seat formed at said mouth and provided with an exhaust port, a tipper provided with an arcuate upper end fitting said seat and having spaced inlet ports, said tipper being divided into a pair of compartments into which said inlet ports respectively open, each of said compartments having a valve at its lower end, and mechanical means to effect oscillation of said tipper to bring each inlet port alternately into registration with the mouth and exhaust port and then out of such registration, and including a crank and a link connecting the crank and tipper, the connection at one end of the link being a pin and slot connection whereby to permit rest of the tipper between successive movements.
- 25 7. The combination with the mouth of a grain hopper, of an arcuate valve seat formed at said mouth and provided with an exhaust port, a tipper provided with an arcuate upper end fitting said seat and having spaced inlet ports, said tipper being divided into a pair of compartments into which said inlet ports respectively open, each of said compartments having a valve at its lower end, and mechanical means to effect oscillation of said tipper to bring each inlet port alternately into registration with the mouth and exhaust port and then out of such registration, and including a crank and a link connecting the crank and tipper, the connection at one end of the link being a pin and slot connection whereby to permit rest of the tipper between successive movements.

formed at said mouth and provided with an exhaust port, a tipper provided with an arcuate upper end fitting said seat and having spaced inlet ports, said tipper being divided into a pair of compartments into which said inlet ports respectively open, each of said compartments having a valve at its lower end, and mechanical means to effect oscillation of said tipper to bring each inlet port alternately into registration with the mouth and exhaust port and then out of such registration, and including a crank and a link connecting the crank and tipper, the connection at one end of the link being a pin and slot connection whereby to permit rest of the tipper between successive movements, said link consisting of sections longitudinally movable with respect to each other and having spring means yieldingly holding said sections in normal relation.

In witness whereof I have hereunto set my hand.

HENRY ORMSBY BURGE,
Executor of Alfred Hillyard Mitchell, deceased.
